United States Patent

Des. 240,977

Patented Aug. 17, 1976

240,977

FABRIC CLOTHING LABEL

Stuart L. Raskas, 24 Westwold Country Club Grounds,
St. Louis, Mo. 63131

Filed Dec. 12, 1974, Ser. No. 532,006

Term of patent 14 years

Int. Cl. D19—08

U.S. Cl. D33—9 C

The figure is a front elevational view of a fabric clothing label of conventional thickness showing my new design.

The drawing is lined to indicate color contrast.

I claim:

The ornamental design for a fabric clothing label, as shown and described.
